HOLDER FOR SEWING ACCESSORIES

Walden J. Boyle, San Francisco, Calif.

Application February 12, 1948, Serial No. 144,428

Term of patent 14 years

(Cl. D3—19)

To all whom it may concern:

Be it known that I, Walden J. Boyle, a citizen of the United States of America, residing at San Francisco, in the county of San Francisco and State of California, have invented a new, original, and ornamental Design for a Holder for Sewing Accessories, of which the following is a specification, reference being had to the accompanying drawing, forming a part thereof.

The figure is a perspective view of a holder for sewing accessories, showing my new design.

The opposite side of the present design is similar to the side shown.

I claim:

The ornamental design for a holder for sewing accessories, substantially as shown and described.

WALDEN J. BOYLE.
